SURFACE PLATE AND METHOD OF MAKING
SAME

William S. Potter, Edgewood, Pa.

Application December 21, 1943; Serial No. 515,141

7 Claims. (Cl. 33—174)

1

This invention relates to surface or gauge plates such as are in general use in tool and die shops for the purpose of laying out work, inspecting and checking the accuracy of work pieces, and also to an improved method of mounting a surface plate in a supporting structure and providing said plate with a working surface having certain practically desirable characteristics.

The present application constitutes a continuation-in-part of my pending application for patent Serial No. 406,733, filed August 13, 1941 which is now abandoned.

The use of cast iron surface plates for the above purpose has been a customary practice in the art for many years. The working surface of the plate is machined and lapped to produce a true, smooth finish so that all points on such surface will, with a maximum degree of accuracy, lie in a common plane. However, after casting such plates they must be aged for a long period to insure against warping and require considerable manual work before lapping. It is a common occurrence in the use of cast iron plates, that, due to accident or carelessness, a heavy object will be dropped on the surface and said surface dented or scratched, resulting in the formation of a burr or elevation of the metal adjacent to the dent or scratch which destroys the trueness of the plate surface. It then becomes necessary to relap the plate to eliminate the burr.

I have succeeded in avoiding these serious objections to the use of cast iron surface plates by the utilization of colored or uncolored plate glass, or analogous material, of suitable surface area and thickness, having a testing surface which, when scratched or chipped, will not require relapping or refinishing. My present invention also contemplates a glass surface plate having an accurately finished working or testing surface of such character that the work piece or gauge block will not wring or stick thereto and which is capable of temporarily retaining thereon markings made by a pencil, or other writing or drawing instrument.

I also provide a novel supporting structure for the glass surface plate and a simple and easily executed method of assembling said plate in fixed relation to the supporting structure, whereby possible flexure or chipping of the glass due to changes in the supporting casting caused by warpage is avoided. Preferably, internal molecular strains in the glass are first removed by annealing and, after mounting the glass plate in the supporting structure therefor, it is then

2

ground by a suitable type of grinder, preferably employing grit segments of silicon carbide, of the vitrified bond type of coarse and fine grit, and of different grades. It has been found that the grinding operation produces a ground surface which is truly flat within a tolerance limit of .0003, more or less. Such a surface also possesses the practical advantages of enabling the work-piece or gauge block to be easily removed therefrom; providing a marking surface upon which computations or drawings may be made; and the easy erasure of such markings and cleansing of the plate surface of oil, grease or dirt.

In addition to the above enumerated objects of the invention, it will be evident from the following detailed description that I have devised a glass surface plate which will be highly accurate in use and may be economically maintained in proper working condition.

With the foregoing and other objects in view the invention consists in the improved surface plate and in the method of assembling the same in a supporting structure, as will be hereinafter more fully described, illustrated in the accompanying drawing and subsequently incorporated in the subjoined claims.

Referring now to the drawing, wherein I have disclosed one preferred structural embodiment of my invention and in which similar reference characters designate corresponding parts throughout the several views:

Figure 1 is a vertical sectional view showing the glass plate as mounted for use in its supporting structure in accordance with my new method;

Figure 2 is a top plan view thereof, the protecting cover being removed;

Figure 3 is a vertical sectional view illustrating the preferred method of assembling the glass plate in the supporting frame or casting;

Figure 4 is a similar view showing a slight modification of said method.

Figures 5 and 6 are vertical sectional views similar to Figure 4, illustrating an alternative method of assembling the gauge plate in its supporting structure; and

Figure 7 is a plan view of the assembly shown in Figure 5.

Referring in greater detail to the drawing, for the purpose of illustration, I have shown a gauge plate 10, preferably of plate glass, either colored or uncolored. This plate has a uniform thickness which is, desirably, not less than approximately one and one-fourth inches and may be of

any predetermined length and width conveniently suitable for a particular purpose or use. In Figure 1 I have shown the plate 10 rigidly locked or supported within a metal frame casting 11. In the present instance this supporting frame is of cast iron and comprises a bottom wall 12, upstanding marginal walls 13 and horizontal flanges 14 extending outwardly from the upper edges of said marginal walls. Preferably, the frame is provided at each of its corners with short supporting legs 15. The internal dimensions of the frame 11 are appreciably greater than the dimensions of the gauge plate 10. This plate is preferably directly supported upon and locked to the frame by embedding it in a body of gypsum composition material 16 or other materials of like characteristics. Such material may be mixed into a fluent mass that has quick-setting properties, and when set provides an underbed of uniform thickness having contact at all points with the lower surface of the plate 10 and immovably supporting said surface throughout the area thereof in uniformly spaced relation from the bottom wall 12 of the supporting frame. The material 16 also extends upwardly between the lateral edge faces of the plate 10 and the marginal walls 13 of the frame 11 to the sealing ring 17, which is preferably putty.

The plate 10 is set in the bed material 16 with its upper surface 18 accurately positioned in the plane of the upper surfaces 19 of the frame flanges 14 and heated pliable sulphur 20, which is impervious to oil, grease or water, is then applied over the putty ring 17. While I have found the putty sealing ring and sulphur finishing strip well adapted for the intended purposes, it is contemplated that various other analogous materials may be employed if desired.

With particular reference to Figure 3 of the drawing, one satisfactory method of preparing the glass plate 10 and fixedly mounting the same in its supporting frame 11 may be described as follows:

First, the glass plate is annealed to remove internal strains and also to avoid possible flexure or chipping after mounting in the frame 11, due to the transference of mechanical stresses to the glass caused by warpage of the frame casting. The plate 10 is then arranged in inverted position with its test surface 18 in contact with the flat surface of a supporting table 21.

The frame casting 11 is provided with a plurality of openings 22 through the bottom wall 12 thereof, and the putty sealing ring 17 is applied to the inner surfaces of the walls 13 and below the upper surfaces of the frame flanges 14. The frame is now also inverted and positioned over the glass plate 10 with the sealing ring 17 in sealing contact with the lateral edge faces of the plate and the frame flanges 14 in contact with the surface of table 21.

The gypsum or like composition, in a semi-liquid, fluent or miscible condition, is now poured at room temperature through the frame openings 22 to completely fill all space above the sealing ring 17 between the plate 10 and frame casting 11. This material will quickly set or harden to provide a locking bed for the plate 10 having substantially uniform density. When in use the plate will thus be properly supported against flexure by the weight of heavy objects placed thereon. The material 16 is heat resistant and non-deformable under such pressures as may be encountered in the use of the gauge plate.

The frame and plate are now turned over and

heated sulphur or equivalent finishing material shown at 20 is applied over the ring 17 and completely fills the remaining space between plate 10 and frame 11.

The surface 18 of plate 10 and the upper surface 19 of the metal supporting frame are now trued by a lapping or grinding machine to quickly bring said surface to the required tolerance limit of flatness. The edges of the frame flanges 14 are also trued with respect to each other and the surface 19 for convenient use in laying out the work. In this grinding operation I have obtained the best results by the use of silicon carbide grinding segments, of a vitrified bond type, composed of coarse and fine grit and of different grades. By the use of such segments a large size plate can be ground in one and one-fourth hours and a small plate in forty minutes, thus giving maximum production with a perfectly finished test surface which has an opaque appearance of ground glass and will receive pencil markings that are readily erased by wiping across them with a finger. This type of surface may also be produced by sand blasting the glass.

The surface plate is now ready for use. The pouring openings 22 in the bottom wall of the frame casting may be closed by suitable plugs, indicated at 23, and a cover 24 provided to protect the test surface 18 when the plate is not in use.

In Figure 4 of the drawing I have shown an alternative spacing means for the putty ring 17. This may consist of a wedging frame 25, preferably of wood, adapted to be positioned in snug fitting relation around the glass plate 10, and in contact with the table 21, prior to placement of the frame 11 thereover. The outer surfaces of the frame 25 may have upper inclined portions 26 which are first engaged by the side walls of the metal frame 11 to force the frame 25 into sealing contact with the edge faces of the plate 10. After the material 16 has properly set the frame 25 may be removed and the space between the frame 11 and plate 10 filled with hot pliable sulphur as above explained.

In Figures 5, 6 and 7 of the drawings I have shown another method of assembling the glass gauge plate in accurately fixed relation with its supporting structure, which may be preferred to the method first above described.

In this alternative method the base casting or frame 11 is first machined, the edges of the legs 15 and surfaces 19 of flange 14 being ground and the edges of flange 14 milled prior to the assembly. The frame is then placed upon the surface 21' of an accurate surface plate, or the top surface of a metal work bench, known to be fairly true. The putty seal 17 is then applied to the inner surfaces of the frame walls 13.

Wood blocks 30 are now inserted through the holes or openings 22' in the bottom wall of the frame casting 11, said blocks resting on the surface 21' and protruding through the openings above the upper surface of the bottom wall 12.

By means of a suction cup device, such as is generally employed in handling glass plates, the plate 10 is now placed in position upon the blocks 30, in centered relation to the frame casting and with its lateral edges equidistantly spaced from the frame walls 13. The blocks 30 are cut to predetermined size so that the surface 18 of the glass plate will be located approximately $1/32$ of an inch above the surface 19 of the frame flange 14. The openings 22' are so located in the frame wall 12 that the support of the glass plate 10

upon the blocks 30 is properly equalized. As in the first described method, the putty seal 17 is placed below the surface 19 of the frame and tightly seals the underlying space between the frame walls 13 and the opposed edges of the glass plate 10.

An angle iron frame 31 is then placed upon the plate 10; the base flange 32 of said frame being of sufficient width to extend outwardly over the major portion of the surface 19 of the supporting frame 11. This base flange has a plurality of spaced openings 33 therein which are positioned in registering relation with the void 34 between the edges of the plate 10 and the frame walls 13, above the putty seal 17. Standard C clamps 35 are now applied to engage the base flange 32 of frame 31 and the lower surfaces of flange 14 of supporting frame 11, at each of the four sides of said frames. The frame 31 is sufficiently rigid so that, as the clamp screws are tightened, the frame casting 11 is raised into contact with the flange 32 of frame 31, and its surface 18 brought into alignment with the surface 18 of the glass plate 10. The complete assembly will then be wholly supported relative to surface 21 by the wood blocks 30.

Pliable sulphur, heated to liquid form, is now poured through the openings 33 into the void 34 between the glass 10 and frame 11. After the sulphur has solidified the clamps 35 and the frame 31 are removed and the frame casting 11, with the glass plate 10 now in accurately centered assembled relation therewith, is lifted off the supporting blocks 30 and turned over with the surface 18 of plate 10 and frame flange 14 in contact with the surface 21'. The gypsum or similar composition is then poured through the openings 22' to completely fill all of the remaining space between the glass plate 10 and the supporting frame or casting 11. After the composition material has properly set or solidified, the assembly is then ready for the final grinding operation to true the surface 18 of plate 10, as above explained. Any slight misalignment which may exist between the surfaces 18 and 19 of the plate 10 and frame 11, respectively, after the assembly is completed, will be eliminated in the final grinding operation.

Of course, it will be understood that in this alternative method, the gypsum or other composition, the putty ring and sulphur seal serve the same advantageous purposes as in the method of assembly first described herein.

The practical advantage of my new gauge plate will be readily appreciated by those familiar with this art. The method employed in making the plate 10 and mounting the same in its supporting frame or casting assures a truly flat testing surface for die blocks or work-pieces, and eliminates the necessity of frequently relapping or grinding said surface to remove burrs or projections thereon resulting from scratches or indentations. Molecular strains in the glass and the transmission of mechanical stresses thereto through the supporting structure are also reduced to a minimum. Thus long life and economical maintenance are realized to offset the somewhat greater production cost, in comparison with the standard cast iron surface plate.

The ground testing surface 18 of the glass plate also has the advantage that metal work-pieces or die blocks do not stick or wring thereon and can be easily lifted therefrom, thus avoiding scratching of said surface. Further, such a surface has the required structural charac-

teristics for erasably retaining computations or sketches made thereon with a suitable marking instrument during the inspection of the work. By the application of a detergent solution such markings, together with grease, oil or dirt which may collect upon the test surface, can be readily removed. Of course, the glass plate can be furnished in a series of different sizes as may be best adapted for the testing of different kinds of work.

I have herein disclosed a structural embodiment of my invention which has given highly satisfactory service. It will, however, be apparent that as to the several details above described, said structure may be exemplified in various other alternative forms.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

30. 1. In a method of mounting a gauge plate in a supporting frame, the steps which comprise; first arranging the frame on a trued supporting surface; then supporting the gauge plate independently of said frame with its lateral edges in spaced opposed relation to the side walls of the frame and its upper surface in a predetermined plane relative to the upper surface of said frame walls; then sealing the space between said frame walls and the gauge plate adjacent said upper surface of the plate, and finally filling the space between the plate and frame walls below the seal with a pressure resistant, non-deformable material to permanently lock the plate against displacement with respect to the frame.
35. 2. In a method of mounting a gauge plate in a supporting frame the steps which comprise; first arranging the frame on a trued supporting surface; then supporting the gauge plate independently of said frame with its lateral edges in spaced opposed relation to the side walls of the frame; then relatively moving the frame and gauge plate vertically with respect to said supporting surface to dispose the upper surfaces of said plate and frame substantially in a common horizontal plane; and then introducing an initially pliable, solidifiable sealing medium into the space between said frame walls and the gauge plate.
40. 3. The method of mounting a gauge plate in a supporting frame which comprises, first arranging the frame on a trued supporting surface, then independently supporting the gauge plate in centered relation to the frame and out of contact with bottom and side walls thereof; then relatively moving the frame and gauge plate vertically with respect to said supporting surface to dispose the upper surfaces of said plate and frame substantially in a common horizontal plane; then sealing the space between said surfaces by the introduction of a pliable solidifiable sealing medium between the edge faces of the gauge plate and the side walls of the frame; and finally introducing between the frame walls and opposed surfaces of the plate an initially plastic composition material to fixedly lock said plate against movement relative to the frame and uni-

formly support the upper surface area of said plate in said horizontal plane.

4. The method of mounting a glass gauge plate in a supporting frame having a base wall and upstanding marginal walls, which comprises, first positioning the plate within the frame and applying a sealing strip in continuous sealing contact with the edge surfaces of the plate and the marginal frame walls, and with the testing surface of the plate substantially flush with the upper edges of said walls, and then introducing an initially miscible composition material between said plate and the frame walls to form a substantially uniformly homogeneous pressure resistant locking bed securing said plate against vertical or lateral displacement relative to the sealing strip and frame walls.

5. The method defined in claim 4, wherein said sealing strip is spaced below the testing surface of the glass plate and finally substantially completely filling said space between the plate and frame walls above the sealing strip, with a heated, solidifiable finishing material.

6. In combination with a metal supporting frame having a base and upstanding marginal walls, a glass gauge plate, and means securing said plate in the frame with its bottom and edge surfaces in spaced substantially parallel relation to the base and marginal walls of the frame and its upper surface disposed in a common plane with the upper surfaces of said marginal walls, said securing means comprising a locking bed of composition material between the frame base

5 and said glass plate having portions thereof partially filling the space between the edge surfaces of the plate and the marginal frame walls, and additional means hermetically sealing the remaining space between said plate surfaces and frame walls.

7. The combination defined in claim 6, wherein said sealing means comprises a continuous sealing strip surrounding the glass plate in contact with the upwardly extending portion of said locking bed, and a finishing strip of sulphur overlying said sealing strip and substantially flush with the upper surface of said plate.

WILLIAM S. POTTER.
